UNITED STATES PATENT OFFICE.

HENRY F. POLLOCK AND HARRY J. HICK, OF ALLIANCE, OHIO, ASSIGNORS TO THE McCASKEY REGISTER COMPANY, (INCORPORATED IN 1914,) OF ALLIANCE, OHIO, A CORPORATION OF OHIO.

FILING-APPLIANCE CASE.

1,299,607.

Specification of Letters Patent.

Patented Apr. 8, 1919.

Application filed December 31, 1914. Serial No. 879,962.

To all whom it may concern:

Be it known that we, HENRY F. POLLOCK and HARRY J. HICK, both citizens of the United States, residing at Alliance, county 5 of Stark, and State of Ohio, have invented certain new and useful Improvements in Filing-Appliance Cases, of which the following is a specification.

The invention relates to a case for a filing 10 appliance or the like, which may include a series of hinged holders operatively mounted therein and adapted to be completely inclosed by the case for protection against fire and like damage.

15 The invention may be embodied in a case having a rectangular base composed of a lower or base section, and an upper or cover section, with guiding hinge connections between the sections, so that the upper section 20 can be closed downward upon the base section to completely incase the bill holders mounted therein, or can be swung upward with its rear end resting upon the rear portion of the base section to form a back or 25 support for the bill holders in operative position.

The upper and lower sections of cases of this character have been made of spaced sheet metal face plates or walls with intervening heat resisting material, with metal bars secured between the rims of the walls, or sheet metal frames telescoped over the same; but such rim bars or frames conduct so much heat that the contents of the case 35 or cabinet cannot be properly preserved and protected from external heat.

The object of the present improvement is to construct the body and rims of cases or 40 cabinets of this character in such a manner that there is no continuous metal contact between the outer and inner metal face plates or walls of the sections; and this object is attained by providing a bar of heat resisting material between the rims of the metal walls, 45 and by securing each wall to said heat resisting bar by means of bolts, rivets or screws which do not extend to or have any metal contact or connection with the other wall.

Sheet metal rim frames or flanges may be 50 provided on the rims of the walls and arranged to extend inward therefrom to the side of the heat resisting bar; which flanges may be arranged to abut corresponding flanges on the rim of the opposing case or

cabinet section; thereby providing a metal 55 contact between the outer and inner portions of opposing rims, without any metallic contact or connection between the outer and inner walls or flanges of the respective rims.

The invention may be embodied and its 60 objects attained in the construction and arrangement illustrated in the accompanying drawings, forming part thereof, in which—

Figure 1 is a side elevation of a filing appliance case containing the improved rim 65 construction;

Fig. 2, a longitudinal section of the same;

Fig. 3, a fragmentary plan view of one corner of the base section of the case, with parts broken away to show details of the 70 rim construction;

Fig. 4, a section on line 4—4, Fig. 3;

Fig. 5, a section on line 5—5, Fig. 3;

Fig. 6, a section showing two opposing 75 rims closed together with portions of the heat resisting material omitted to show details of construction, and

Fig. 7, a detached view of one abutment chair or bracket.

Similar numerals refer to similar parts 80 throughout the drawings.

The case may be composed of the substantially similar rectangular base or bottom section 1, and the cover or top section 2, which are operatively connected together by 85 means of the guiding hinge brackets 3, one being located on each side of the rear end portion of the case. A series of bill holders 4 may be hinged together at their rear ends, and one of the holders may have its hinged 90 end pivoted to the rear end rim of the cover section.

An index frame 5 may be pivoted at its rear end to the hinged end of the lower frame, and may have its forward end supported by guiding means 6 for directing it forward and rearward out of and into the case. Counterbalance means 7 may also be provided for the case sections and the bill holders, but these devices do not form any 100 part of the present invention and need not be described in detail.

Each case section is preferably made of an outer and inner sheet metal face plate or wall 8 and 8'; which walls are pressed or 105 otherwise formed to the rectangular shape of the case section, and the outer wall 8 is made enough larger than the inner wall 8',

so that the walls may be spaced apart at all points to form an intervening cavity which is filled with a heat resisting material 9 to form a fire proof structure.

5 The rims of the walls 8 and 8^a may be connected together by means of the intervening rim bar 10 composed of heat resisting or insulating material which is preferably made of transite asbestos wood, or other like substance. When it is desired to provide one or more metal contact faces, for the abutting edges of the rims of separable case sections, the L-shaped rim frames or flanges 11 are provided on one or both sides of the 10 rim bar 10, which frames have their wider outer flange 12 integral with or secured by brazing or riveting to the outer sides of the wall rims; and preferably have their narrower inner flanges 13 inclined or beveled 15 inward, so that the free edges only thereof will contact with the heat resisting rim bar.

The metal walls and rim flanges may be secured to the intervening rim bar by means of the rivets 14 or the screws 15, and suitable abutment chairs 16 of the same depth as the rim flanges, are preferably provided between each metal wall and the rim bar, to properly space the same apart; one chair being used for each rivet or screw, and each 30 chair being provided with the central aperture 17 for receiving the shank of the same.

In the preferred form of construction illustrated in the drawings, rivets 14 are used for securing the outer metal wall to 35 the rim bar, and a washer 18 is used on the inner end of each rivet. As shown in the drawings, these rivets do not extend inward far enough to contact with the inner metal wall, and the interval between the inner head 40 of the rivet and the inner wall is filled with the heat resisting material 9. And in the same form of construction, the inner metal wall is secured to the rim bar by means of the screws 15 which pass through into, but 45 not beyond the rim bar. The securing rivets and screws are staggered or spaced apart along the rim so that neither the rivets or screws, nor the abutment chairs, will contact with each other; and the abutment 50 chairs are also so proportioned that they will not contact with any portion of the rim flanges.

The preferred method of assembling the parts is by securing the rim bar to the outer 55 metal wall and rim flange by means of the rivets 14, and then inserting the inner metal wall and rim flange into proper position inside the rim bar and securing these parts together by means of the screws 15, by which 60 arrangement of the parts the heads of rivets only are exposed on the outer side of the case or cabinet; after which the heat resisting material 9 may be inserted between the metal walls, as for instance, by injecting it 65 in a liquid or powdered form through an

aperture in one of the walls, and then plugging or otherwise closing the aperture.

By this construction and arrangement, it is evident that a strong and substantial rim is provided for connecting the spaced edges 70 of the metal walls, which rim also serves to close the spaced interval between the edges and forms a completely closed cavity between the metal walls for the reception of the heat resisting material. And it is furthermore evident that there is no continuous metal connection or contact between the outer and inner walls for conducting heat 75 from one wall to the other.

As shown in Fig. 6, the rim faces of the 80 L-shaped flanges may be arranged to impinge the corresponding faces of an opposing rim, thereby providing a metallic contact to receive the pressure and wear of the rim joint, and rendering it immaterial 85 whether the rim edge of the rim bars shall impinge or contact with each other or not. And these several rim faces may be arranged in stepped relation, thereby forming 90 a series of rabbets in the completed rim, by the intermeshing of which a tightly sealed joint may be obtained by the use of suitable clamping means, as for instance, the locking bolt 19, conventionally shown in Fig. 2.

The triangular space between the inclined 95 inner portion of each L-flange which is adjacent to the side of the rim bar, may be filled by suitable heat resisting material; and it is evident that the inclination of these flanges which extend beyond the edge of the 100 rim bar, avoids a rubbing contact with the corresponding bar of an adjacent rim and prevents an abrasion of the same.

We claim:

1. A case or cabinet section having spaced 105 walls of metal with intervening heat resisting material, and means for connecting the rim portions of the walls together, including an insulating bar and a plurality of separate connections between the bar and 110 each wall, the several connections being spaced from the other wall and from each other.

2. A case or cabinet section having spaced 115 walls of metal with intervening heat resisting material, an insulating bar interposed between and spaced from the rim portions of the metal walls, means for securing the insulating bar to the wall including a plurality of separate connections between the 120 bar and each wall, the several connections being spaced from the other wall and from each other, and spacing means between the insulating bar and the walls.

3. A case or cabinet section having spaced 125 walls of metal with intervening heat resisting material, a bar of heat resisting material between the rims of the walls, an L-flange on one of the wall rims contacting 130 with the rim bar, and means for securing 135

- the rims together including a plurality of connections between the bar and each wall and an abutment between the wall and the bar for each connection, the several connections being spaced from the opposite wall and from each other.
4. A case or cabinet section having spaced walls of metal with intervening heat resisting material, L-flanges on the rims of the walls, a rim bar of heat resisting material between the flanges, and means for securing the rims together including a plurality of connections between the bar and each wall and an abutment between the wall and the bar for each connection, the several connections being spaced from the opposite wall and from each other.
5. A case or cabinet section having spaced walls of metal with intervening heat resisting material, L-flanges on the rims of the walls, a rim bar of heat resisting material between the flanges, and means for securing the rims together including a plurality of connections between the bar and each wall and an abutment between the wall and the bar for each connection, the several connections being spaced from the opposite walls and from each other and the exposed faces of the flanges and the rim bar being arranged in stepped relation.
6. A case or cabinet including two sections, each section having spaced walls of metal with intervening heat resisting material, a rim bar of heat resisting material between the rims of the metal walls, corresponding walls of each section being spaced from the bars and having L-flanges contacting with and inclined from the rim bars, and means securing the rims together including a plurality of connections between each bar and one of the walls, an abutment between the wall and the bar for each connection, the several connections being spaced from the opposite wall and from each other, and the exposed faces of the rim parts being arranged so that the rim faces of the flanges will contact when the opposing rims are closed together.
7. A case or cabinet including two sections, each section having spaced walls of metal with intervening heat resisting material, a rim bar of heat resisting material between the rims of the metal walls, corresponding walls of each section being spaced from the bars and having L-flanges contacting with and inclined from the rim bars, and means securing the rims together including a plurality of connections between each bar and one of the walls, an abutment between the wall and the bar for each connection, the several connections being spaced from the opposite wall and from each other, and the exposed faces of the rim parts being arranged so that the flange faces will contact when the opposing rims are closed together.
